Siro R. Toffolon, Meriden, Conn., assignor to General
Time Corporation, Stamford, Conn., a corporation of
Delaware

Filed Oct. 11, 1968, Ser. No. 13,953

Term of patent 14 years

Int. Cl. D10—01

U.S. Cl. D42—7

7 7 2

FIG. 1 is a front perspective view of a clock casing showing my new design, the fragmentary cross-hatching within the frame indicating a material having the appearance of an open-weave fabric;

FIG. 2 is a front elevational view;

FIG. 3 is a left side elevational view;

FIG. 4 is a top plan view; and

FIG. 5 is a bottom view.

The rear, not shown, is plain and unornamented.

The broken line showings are for illustrative purposes only.

I claim:

The ornamental design for a clock casing, substantially as shown and described.
